(57) **CLAIM**

The ornamental design for a freight load bar securement accessory, as shown and described.

DESCRIPTION

FIG. 1 is a bottom perspective view of a freight load bar securement accessory, showing our new design; FIG. 2 is a top perspective view thereof;

FIG. 3 is a front elevational view thereof;

FIG. 4 is a rear elevational view thereof;

FIG. 5 is a left-side elevational view thereof, the right-side elevational view being a mirror image thereof;

FIG. 6 is a top plan view thereof;

FIG. 7 is a bottom plan view thereof; and,

FIG. 8 is a cross-sectional view thereof, taken along line 8-8 of FIG. 7.
